UNITED STATES PATENT OFFICE.

LYNN S. PACE, OF CISCO, UTAH.

DRIVING APPARATUS FOR HORSES AND OTHER ANIMALS.

1,257,734.

Specification of Letters Patent. Patented Feb. 26, 1918.

Application filed April 25, 1917. Serial No. 164,480.

To all whom it may concern:

Be it known that I, LYNN S. PACE, a citizen of the United States, residing at Cisco, in the county of Grand, State of Utah, have 5 invented certain new and useful Improvements in Driving Apparatus for Horses and other Animals; and I do hereby declare the following to be a full, clear, and exact description of the invention, such as will enable others skilled in the art to which it 10 pertains to make and use the same.

This invention is an improvement in steering mechanism and has particular reference to an apparatus for driving horses 15 and other animals.

An object of the invention is the provision of an improved apparatus wherein an animal may be guided and brought to a standstill without the necessity of the 20 driver handling the reins and, to this end, use is made of a pair of drums upon which the reins are mounted and which are controlled by a steering wheel, by which term is meant the wheel proper or parts directly 25 associated therewith, operatively connected to a gear mechanism actuated by said wheel to simultaneously rotate said drums in opposite directions to tauten the reins and, in the same direction, to wind one of the reins 30 on its drum and unwind the other rein from its respective drum.

Another object is to provide a support for the reins adjustably mounted and actuated by foot controlled means for tautening or 35 drawing in the reins to stop the animal without the necessity of employing the mechanism, forming a part of the steering wheel, for simultaneously tautening the reins.

40 The inventive idea involved is capable of receiving a variety of mechanical expressions, one of which, for the purpose of illustrating the invention, is shown in the accompanying drawings; but it is to be expressly understood that said drawings are 45 used only to facilitate the description of the invention as a whole and not to define the limits thereof, reference being had to the appended claims for this purpose.

50 In the drawings:—

Figure 1 is a side elevation of the apparatus constructed in accordance with the invention.

55 Fig. 2 is an enlarged side elevation of the drums and the gear mechanism for operat-

ing the same, the casing therefor being shown in section.

Fig. 3 is a section on the line 3—3 of Fig. 2.

Fig. 4 is a section on the line 4—4 of 60 Fig. 2.

Fig. 5 is a central vertical longitudinal section through the casing.

Fig. 6 is a top plan view of the steering wheel and associated parts. 65

Fig. 7 is a detail side elevation of a locking device associated with the steering wheel and shown in unlocked position.

Fig. 8 is a similar view of the device and a portion of the steering wheel showing the 70 locking device in locked position.

Fig. 9 is a detail side elevation of another locking device employed in connection with the invention and associated with the rein support. 75

Fig. 10 is an edge elevation thereof.

Fig. 11 is a front elevation of the upper end of the rein support.

Fig. 12 is a top plan view of a guide plate carried by the casing for retaining the reins 80 in position.

The invention is illustrated in the accompanying drawings in what is now believed to be its preferred form and comprises a sectional casing 15 having its bottom secured 85 to the floor of a carriage or other vehicle in front of the driver's seat and adjacent the dash board. The major portion of the casing is arranged diagonally and has extending from its top side a rotatable hollow 90 steering shaft 16 and an inner shaft 17 extending longitudinally of the first named shaft and beyond the inner end thereof and through the casing 15. The outer shaft 16 is provided with a bracing member 18 consisting of downwardly diverging arms 19 and 20, the former arm being secured to one end of a brace arm 21 carried by the casing, said arm 19 having an extension 22 for a purpose which will appear in the course of 10. 100 the description. The casing 15 carries a stationary supporting frame 23 having at its upper end an extension 24 provided with a laterally projecting stop lug 25. This frame 23 has mounted adjacent its upper end a shaft 26 to which the lower ends of the arms 20 of the bracing member 19 are connected and pivotally mounted upon this shaft 26 is a rein supporting frame 27, preferably of an inverted substantially U-shaped forma-

105
110

tion having mounted in its upper end a pair of pulleys 28 over which the left and right reins 29 and 30, respectively, pass. This rein supporting frame 27 extends sufficiently high to allow the reins to pass therefrom over the dash board of the vehicle and to the horse's head and said frame is provided at one of its ends with an extension 31 having a plurality of notches 32 in its upper surface, any one of which is adapted to be engaged by one end of a retractile coil spring 33, the other end of which is connected to the extension 22 of the brace arm 19 whereby the frame 27 is normally retained in position with its upper end withdrawn in a rearward direction so that the reins will be tautened and any pull upon said reins, by reason of the animal tossing its head, will pull the upper end of the frame 27 forwardly against the tension of the spring 33 and said tension may be varied by engaging the upper end thereof in any one of the notches 32. The forward motion of the frame 27 is limited by contact of the side member thereof, having the extension 31, with the lug 25 formed upon the extension 24 of the frame 23.

A locking device is provided in connection with the frame 27 for retaining the same in a forward position so that the reins 29 and 30 will be loose when the animal is standing still and is most likely to toss its head. This locking device comprises a latch member 34 pivoted to the frame 27 and movable between the stop pins 35 which limit the movement of said latch. A lever 36 is pivoted at 37 to the frame 27 and is provided with an operating handle 38 and an offset 39 which is adapted to engage an extension 40 formed upon one end of the latch member 34 whereby to normally hold said latch member in inoperative position as shown in dotted lines in Fig. 9, the lever 36 being yieldably retained in its adjustable positions by means of a coil spring 41 having one end connected to a pin 42 carried by the lever and its other end connected to a similar pin 43 carried by the frame 27. Should it be desired to lock the frame 27 in a forward position, the lever 36 is swung to the full line position shown in Fig. 9 whereupon the latch 34 will swing to operative position and the locking end thereof will thus engage over the lug 25 and prevent a return movement of the frame 27, under the action of the spring 33, until the lever 36 is again shifted to its dotted line position.

The opposite side of the frame 27 from that carrying the locking device, just described, is preferably provided with a laterally extending foot pedal 44 adapted to be engaged by a foot of the operator and pushed forwardly to rock the frame 27 about the shaft 26 as a pivot and thus throw the upper end of the frame in a rearward di-

rection which will pull in on the reins and thereby exert sufficient pull upon the animal's head to bring it to a stand still.

The winding and unwinding mechanism for the reins 29 and 30 is illustrated in Figs. 2 to 5 inclusive, and preferably comprises a pair of drums, generally indicated by the numerals 45 and 46, mounted interiorly of the casing 15 in spaced relation, the drum 45 having connected thereto, in a manner to be presently described the right hand rein 30 while the drum 46 has connected thereto the left hand rein 29 at a diametrically opposite point from that at which the rein 30 is connected to its drum. It will be apparent from this arrangement that the reins will both be wound or unwound from their respective drums when the latter are rotated in opposite directions and that when said drums are rotated in the same direction one of the reins will be wound upon its drum while the other rein will be unwound from its drum.

The means for securing the ends of the reins to the drums 45 and 46 preferably comprises a hook 47 formed upon one of the spokes 48 of each of the drums and having associated therewith a leaf spring 49 one end of which is secured to an adjacent spoke while its free end is arranged contiguous to the hook 47 and forms a spring latch for the ring 50 secured to the inner end of the rein which is wound upon the drum. The periphery of each drum is preferably flanged and the flanges thereof have mounted therebetween a relatively stationary ring member 51 having its ends secured together at 52 and supported in position by means of a substantially V-shaped bracket 53 secured to the interior of the casing at any desired point by means of fasteners 54. Each ring member 51 is provided with an elongated slot 55 through which the rein on the drum extends.

The upper end of the casing 15 preferably has secured thereto an angular plate 56, best illustrated in Fig. 12, provided with diagonally arranged stub shafts 57 upon which is mounted a flanged pulley 58 with which is associated a guide 59 for preventing the rein passing over said pulley becoming accidentally detached therefrom. The stub shafts 57 are diagonally disposed in order that the reins passing thereover may be properly led to the pulleys 28 without riding over the flanges of either of the pulleys 58 and becoming jammed between said pulleys and the guide 59.

As previously stated, in order to tauten the reins 29 and 30 it is necessary to rotate the drums 45 and 46 in opposite directions and, for this purpose, the drum 45 is provided upon its inner surface, that is the surface adjacent the drum 46, with a large beveled gear 60 mounted in the bearings 61

which support the alined shafts 62 each of which carries upon one end a small gear 63, and is provided adjacent its other end with a similar gear 64. These gears 64 mesh with 5 the large gear 60 carried by the drum 45 and also mesh with a large gear 65 carried by the inner face of the drum 46. Preferably keyed upon the inner shaft 17 which extends through the casing 15 is a bevel gear 66 10 which meshes with the gears 63 so that when the shaft 17 is rotated in either direction, in a manner to appear in the course of the description, the gears 63 will be driven in opposite directions and through the intermediary of the shafts 62, gears 64 and gears 15 60 and 65, the drums 45 and 46 will be rotated in opposite directions so as to wind the reins thereupon.

In guiding or steering the animal it is necessary that the drums 45 and 46 be simultaneously rotated in the same direction, depending upon the direction of travel, and, in order to accomplish this result, the outer rotatable shaft 16 carries at its lower end, 25 interiorly of the casing 15, a large gear wheel 67 meshing with a small gear 68 carried upon one end of a shaft 69 extending transversely of the casing 15 and journaled therein and having, intermediate its ends, a second gear wheel 70. This gear 70 meshes with a large gear 71 preferably provided with oppositely disposed openings or sockets 30 72 for receiving the adjacent outer ends of the shafts 62 whereby rotation of said gear 35 71 will impart a rotary movement in the same direction relative to the longitudinal axis of the shaft 17, to the shaft 62, gears 63 and 64 and consequently the drums 45 and 46.

40 The upper end of the outer shaft 16 has preferably secured thereto a steering wheel 73 which is employed for the purpose of operating the gears 67, 68, 70 and 71 to rotate the drums 45 and 46 in the same direction whereby one of the reins is wound upon 45 its drum and the other rein unwound from its drum.

The operation of rotating the drums in opposite directions whereby both reins are 50 wound upon their respective drums, is accomplished through the rotation of the inner shaft 17, as previously described, independently of the rotation of said shaft 16 and in order to rotate the shaft 17 the same 55 has secured thereto, at its upper end, a lever 74 which moves over a ratchet wheel 75 secured to the spokes of the steering wheel 73. The lever 74 is preferably locked to the ratchet wheel 75 so that said lever will rotate 60 with the steering wheel when the latter is actuated and for this purpose there is provided a latch member 76 pivotally carried by the outer end of the lever 74 and having a ratchet tooth engaging end 77 which is 65 normally maintained in engagement with

one of the teeth of the ratchet wheel 75 by means of a leaf spring 78 carried by the lever 74 and engaging an extension 79 of the latch member 76. When it is desired to adjust the lever 74 relative to the steering 70 wheel 73, it is only necessary to swing the latch member 76 inwardly, against the tension of the spring 78, about its pivot and disengage the end 77 from the ratchet wheel 75. If desired, the latching member 76 may 75 be retained in its unlocked position by means of a small bell crank lever 80 pivoted to the outer end of the lever 74 and adapted to be swung to the position shown in Fig. 7 whereupon one end will engage a shoulder 81 80 formed upon the latching member 76.

What is claimed is:—

1. In an apparatus of the character described, the combination with driving reins; of rotatable drums for said reins having a 85 common axis, and a shaft for rotating said drums in opposite directions to wind the reins thereon and having its longitudinal axis parallel with that of said drums.

2. In an apparatus of the character described, the combination with driving reins; of rotatable drums for said reins having a common axis, and a shaft having its longitudinal axis parallel with that of said drums and adapted to rotate the same in the same 95 direction to wind one of the reins on its drum and unwind the other rein from its drum.

3. In an apparatus of the character described, the combination with driving reins; 100 of a drum for each rein, means for rotating said drums in opposite directions to wind the reins thereon, and means for rotating said drums in the same direction to wind one of the reins on its drum and unwind the 105 other rein from its drum.

4. In an apparatus of the character described, the combination with driving reins; of rotatable drums for said reins having a 110 common axis, and a shaft having its longitudinal axis coincident with that of said drums and adapted to rotate the same in opposite directions to wind the reins thereon.

5. In an apparatus of the character described, the combination with driving reins; of a drum for each rein, a train of gearing operable to rotate the drums in opposite directions to wind the reins upon their respective drums, and other gearing associated 120 with said train of gearing and operable to rotate said drums in the same direction to wind one of the reins on its drum and unwind the other rein from its drum.

6. In an apparatus of the character described, the combination with driving reins; of a drum for each rein, a train of gearing operable to rotate the drums in opposite directions to wind the reins upon their respective drums, and a rotatable shaft having 130

its longitudinal axis parallel with that of said drums for operating said train of gearing.

7. In an apparatus of the character described, the combination with driving reins:

of a drum for each rein, a train of gearing operable to rotate the drums in opposite directions to wind the reins upon their respective drums, a rotatable shaft having its axis of rotation coincident with that of said drums for operating said train of gearing, and a hand lever for actuating said shaft.

8. In an apparatus of the character described, the combination with driving reins:

15 of a drum for each rein, a train of gearing operable to rotate the drums in opposite directions to wind the reins upon their respective drums, other gearing associated with said train of gearing and operable to 20 rotate said drums in the same direction to wind one of the reins on its drum and unwind the other rein from its drum, a rotatable shaft for operating said train of gearing, and a second rotatable shaft surrounding the first named shaft for actuating said other gearing.

9. In an apparatus of the character described, the combination with driving reins:

30 of a drum for each rein, a train of gearing operable to rotate the drums in opposite directions to wind the reins upon their respective drums, other gearing associated with said train of gearing to wind one of the reins on its drum and unwind the other rein from 35 its drum, a rotatable shaft for operating said train of gearing, a second rotatable shaft surrounding the first named shaft, for actuating said other gearing, a lever for actuating the first named shaft, and a steering wheel for actuating the second named shaft.

10. In an apparatus of the character described, the combination with driving reins:

45 of a drum for each rein, a train of gearing operable to rotate the drums in opposite directions to wind the reins upon their respective drums, other gearing associated with said train of gearing to wind one of the reins on its drum and unwind the other rein from 50 its drum, a rotatable shaft for operating said train of gearing, a second rotatable shaft surrounding the first named shaft for actuating said other gearing, a lever for actuating the first named shaft, a steering wheel for actuating the second named shaft, and means for locking said lever to said steering wheel when the latter is being operated to rotate said second shaft.

60 11. In an apparatus of the character described, the combination with driving reins:

of a drum for each rein, a train of gearing operable to rotate the drums in opposite directions to wind the reins upon their respective drums, a rotatable shaft for oper-

ating said train of gearing, and means for bodily rotating said train of gearing about the longitudinal axis of said shaft as a center, to cause said drums to rotate in the same direction.

70 12. In an apparatus of the character described, the combination with driving reins:

of a drum for each rein, a train of gearing operable to rotate the drums in opposite directions to wind the reins upon their respective drums, a rotatable shaft for operating said train of gearing, means for bodily rotating said train of gearing about the longitudinal axis of said shaft as a center to cause said drums to rotate in the same direction, and a second rotatable shaft for operating the last named means.

75 13. In an apparatus of the character described, the combination with driving reins:

80 of a drum for each rein, a train of gearing operable to rotate the drums in opposite directions to wind the reins upon their respective drums, a rotatable shaft for operating said train of gearing, means for bodily rotating said train of gearing about the longitudinal axis of said shaft as a center to cause 85 said drums to rotate in the said direction, a second rotatable shaft for operating the last named means, and means for locking the first named shaft to said second named shaft 90 when the latter is actuated whereby said shafts will rotate together.

14. In an apparatus of the character described, the combination with driving reins:

95 of a drum for each rein, means operable to 100 rotate the drums in opposite directions to wind the reins upon their respective drums, means for operating the first named means, and means for bodily rotating said first named means about the second named means 105 as a center to cause said drums to rotate in the same direction.

15. In an apparatus of the character described, the combination with driving reins:

110 of a drum for each rein, means operable to 110 rotate the drums in opposite directions to wind the reins upon their respective drums, a rotatable shaft for operating the first named means, means for bodily rotating said first named means about the longitudinal axis of said shaft as center to cause said drums to rotate in the same direction, and a second rotatable shaft for operating the second named means.

16. In an apparatus of the character de-

scribed, the combination with driving reins:

120 of means upon which said reins are wound to tauten the same, means including a steering wheel for actuating the first named means to wind the reins thereupon, and 125 means operatively connected to the last named means and adapted to actuate the same to wind one of the reins on the first named means and unwind the other rein therefrom.

17. In an apparatus of the character described, the combination of a stationary frame, a rein supporting member pivoted thereto and to which the reins are connected, 5 said supporting member having an extension, means connected to the extension for normally and yieldably holding the reins tautened, means forming a part of said supporting member and operable in the direction of the animal for adjusting the same to further tauten said reins to stop the animal, 10 means forming a part of said frame for limiting the movement of said supporting mem-

ber in opposite direction, and a catch carried by said supporting member and engageable with the last named means to releasably retain said supporting member at the extremity of its movement in said opposite direction. 15

In testimony whereof I affix my signature 20 in the presence of two witnesses.
